UNITED STATES PATENT OFFICE

161,336

DRAWING PEN

Harlan N. Harris, Los Angeles, Calif.

Application March 2, 1948, Serial No. 144,877

Term of patent 14 years

(Cl. D74—17)

To all whom it may concern:

Be it known that I, Harlan N. Harris, a citizen of the United States, residing at Los Angeles, in the county of Los Angeles and State of California, have invented a new, original, and ornamental Design for a Drawing Pen, of which the following is a specification, reference being had to the accompanying drawing, forming part thereof:

Fig. 1 is a front view of a drawing pen showing my design.

Fig. 2 is a side view thereof.

The essential features of my design for a drawing pen reside in the shortness of the nib portion in comparison with the full length of the entire article, all as illustrated.

I claim:

The ornamental design for a drawing pen, substantially as shown and described.

HARLAN N. HARRIS.
